(57) **CLAIM**

The ornamental design for an ultrasonic surgical aspiration tip, as shown and described.

DESCRIPTION

FIG. 1 is a top perspective view of an ultrasonic surgical aspiration tip showing our new design;

FIG. 2 is a right side view thereof, the left side view being the same thereto;

FIG. 3 is a top plan view thereof, the bottom plan view being the same thereto;

FIG. 4 is a front view thereof;

FIG. 5 is a rear view thereof; and,

FIG. 6 is an enlarged fragmentary view of the tip portion thereof.
